GEORGE N. LAMB, OF ST. CHARLES, ILLINOIS

ROAD-TESTING MACHINE

Application filed December 22, 1928. Serial No. 327,895.

My invention relates to an improved construction of machine for testing roadways to determine whether they are level and true. In constructing roadways where the surface is of considerable extent at the same inclination, whether on a level run of roadway or on a grade, it is customary in the specification of the roadway to permit a small amount of variation from exact longitudinal alignment, for example, one quarter of an inch in ten feet, and the inspection of such roadways requires considerable care to determine whether the specification has been observed in the particular referred to. By my present invention, I provide a machine consisting of two frame members pivotally connected at their adjacent ends so that the machine may be folded into compact compass when not in use, and wheels preferably mounted at the pivot connection of the frame members and at their other ends, to support the machine on the roadway being tested. It is desirable that the length of the entire machine shall be substantial, for example, ten feet, to accurately determine the condition of the roadway as to alignment of its surface, and while I have heretofore employed similar machines having a rigid frame member, I find it is difficult to house the machines when not in use; my present invention provides for folding the machine to obviate that disadvantage.

With my present invention, one of the frame members carries at its mid portion, adjustable stops between which the end of a bar may move which is supported by the other frame member, and in this way variations in evenness of the roadway are indicated by movement of the end of the bar between the adjustable stops. With the proportions referred to, where the frame members are of the same length between the axes of their supporting wheels, the movement of the bar between the adjustable stops is substantially equal to the displacement of the mid wheel from alignment with the end wheels. By my construction, I further provide a support for the indicating bar so that it may collapse when the machine is folded.

My invention will best be understood by

reference to the accompanying drawings showing a preferred embodiment thereof, in which

Fig. 1 illustrates my machine in its condition when in use, in side elevation,

Fig. 2 shows the machine illustrated in Fig. 1, in side view in its folded condition,

Fig. 3 is a sectional view to an enlarged scale, of the parts shown in Fig. 1 taken along the line 3—3,

Fig. 4 is a sectional view to an enlarged scale, of the parts shown in Fig. 1 taken along the line 4—4, and

Fig. 5 is a detailed plan view of the hinged construction and wheel mounting of the machine.

Similar numerals refer to similar parts throughout the several views.

As shown in Fig. 1, my machine consists of two frame members 10 and 11 provided at their ends with forked brackets 12, 13 and 14, 15 respectively. The ends of the bracket 14 overlap the ends of the bracket 13 and are connected by a pivot rod 16 forming the axle of a wheel 17 and constituting a hinged construction supporting the mid-portion of the machine, as shown in Fig. 5. The brackets 12 and 15 similarly support the end wheels 18 and 19. The ends of the brackets are offset downwardly from the frame members, to facilitate folding the machine when it is not in use.

The frame member 11 carries mid-way between the wheels 17 and 19, two adjustable stops 20 and 21, for example screws, threaded through supporting arms 22 and 23 carried by a bracket 24 secured to the frame member 11. The frame member 10 carries by suitable brackets 25 and 26, a metal tube 27, preferably substantially parallel with the frame member 10, said tube being about half as long as the frame member. The tube 27 contains a bar 28 which is preferably a sliding fit in the tube, said bar being of a length to extend adjacent the stop screws 20 and 21 and at the same time to project sufficiently into the tube 27, to give the bar positive support. The end of the bar 28 adjacent the stop screws 20 and 21, preferably carries a plate 29 which extends between the stop screws 20 and 21.

and 21 so that movement of the bar vertically, relatively to the frame member 11, is limited by the stop screws. A bracket 30 comprising a bent metal bar, is carried by the frame member 11 adjacent the stop screws 20 and 21, around the bar 28 to protect it from being bent while in use, and yet permitting free movement of the bar vertically. The bar 28 is preferably of metal and may be either solid or tubular as desired.

While the construction thus far described affords a visible indication of surface irregularities by movement of the plate 29 vertically between the stop screws 20 and 21 when the machine is rolled over a roadway being tested, I find it convenient to employ in addition, an audible indication of movement of the plate 29 to the limits of the tolerance permitted in either direction, and this result is secured by mounting on the frame member 11 by means of a bracket 31, an electric battery 32 and an electric buzzer 33, electrically connected with the arms 22 and 23 and with the plate 29 as indicated, the arms 22 and 23 for this purpose being insulated from the bracket 24.

For the construction described, where the distances between the wheels are equal to each other, and the axis of the stop screws 20 and 21 is mid-way between the wheels 17 and 19, the plate 29 will move between the stop screws 20 and 21 amounts substantially equal to the displacement of the wheel 17 from alignment with the wheels 18 and 19, and by setting the stop screws 20 and 21, at distances above and below the plate 29 equal to permissible variations in the level or alignment of the roadway, an indication is at once had of irregularities in the surface of the roadway being within or greater than the permissible variation from a straight line of the surface of the roadway, for with the electrical connections described, the buzzer 33 gives an audible indication when the vertical displacement of the wheel 17 from alignment with the wheels 18 and 19 reaches said permissible variation in either direction.

A bracket 34 is preferably mounted on the axle of the wheel 19 to form a stand for the machine by swinging the bracket to vertical position, and from the upper end of the bracket, a handle 35 extends to conveniently move the machine along the roadway being tested.

As shown in Fig. 3, the frame member 10 may conveniently consist of two light channel bars 10^a and 10^b of metal, secured together at intervals by rivets or equivalent fastening devices, and in this figure I illustrate the construction of the bracket 25, which consists of a metal bar bent to form a seat at its mid-portion for the tube 27, and having its ends extending upon opposite sides 65 of the frame member 10 and secured thereto

by bolts 36. The tube 27 is held in its seat by a cap 25^a fastened to the bracket 25 by suitable screws or bolts. The bracket 26 is of the same construction as the bracket 25.

In Fig. 4 I illustrate the construction of the bracket 30, which is bent at its mid-portion to form a vertical guideway for the bar 28, and has its ends extending upon opposite sides of the frame member 11 to which it is secured by suitable bolts 37. The frame member 11 is preferably of the same construction as described for the frame member 10 and as shown in Fig. 4 may consist of light channel bars 11^a and 11^b of metal, secured together in any suitable manner, for example by rivets.

In the folded relation of the machine shown in Fig. 2, it will be observed that the frame members lie adjacent each other in substantially parallel relation, and in this view I illustrate the collapsed position of the rod 28 in the tube 27, so that the plate 29 does not extend beyond the wheel 17. A clamping screw 38 may extend through the bracket 26 and the tube 27, to hold the rod 28 either in the position shown in Fig. 1 or the position shown in Fig. 2 as desired.

My construction above described provides an accurate and dependable indicating mechanism for determining the condition of a roadway as to straightness of its surface, and at the same time affords a construction that may be folded into small space as shown in Fig. 2, to facilitate moving the machine from one location to another and storing the machine when it is not in use.

While I have shown my invention in the particular embodiment above described, it will be understood that I do not limit myself to this exact construction as I may employ equivalents known to the art at the time of the filing of this application without departing from the scope of the appended claims.

What I claim is:

1. In a road testing machine, the combination of two elongated longitudinally aligned frame members, a hinge construction pivotally connecting the adjacent ends of said members, a wheel rotatably mounted in said hinge construction, an additional wheel rotatably mounted on the end portion of each of said frame members remote from said hinge construction, a rod carried by one of said frame members and extending beyond said hinge construction and adjacent said other frame member, and a gauge point carried by said other frame member adjacent the end of said rod and adapted to show vertical movement of said rod end relatively to said gauge point, whereby movement of one of said wheels vertically relatively to the others of said wheels moves said rod end relatively to said gauge point.

2. In a road testing machine, the combination of two elongated longitudinally aligned

frame members, a hinge construction pivotally connecting the adjacent ends of said members, a wheel rotatably mounted in said hinge construction, an additional wheel rotatably mounted on the end portion of each of said frame members remote from said hinge construction, a rod carried by one of said frame members and extending beyond said hinge construction and adjacent said other frame member, and a gauge point carried by said other frame member adjacent the end of said rod and adapted to show vertical movement of said rod end relatively to said gauge point, whereby movement of one of said wheels vertically relatively to the others of said wheels moves said rod end relatively to said gauge point, the distances from the axis of said mid-wheel to the axis of the other wheels being substantially equal to each other, said gauge point being equidistant from the axes of the wheels carrying its supporting frame member, and said wheels being of substantially the same diameter, whereby movement of the mid-wheel relatively to the plane of the tread surfaces of said additional wheels produces a substantially equal relative movement between said rod and said gauge point.

3. In a road testing machine, the combination of two elongated longitudinally aligned frame members, a hinge construction pivotally connecting the adjacent ends of said members, a wheel rotatably mounted in said hinge construction, an additional wheel rotatably mounted on the end portion of each of said frame members remote from said hinge construction, a rod carried by one of said frame members and extending beyond said hinge construction and adjacent said other frame member, a gauge point carried by said other frame member adjacent the end of said rod and adapted to show vertical movement of said rod end relatively to said gauge point, whereby movement of one of said wheels vertically relatively to the others of said wheels moves said rod end relatively to said gauge point, and a tube carried by said one frame member and supporting said rod, whereby said rod may be moved into said tube to lie between the ends of said one frame member when the machine is not in use.

4. In a road testing machine, the combination of two elongated longitudinally aligned frame members, a hinge construction pivotally connecting the adjacent ends of said members, a wheel rotatably mounted in said hinge construction, an additional wheel rotatably mounted on the end portion of each of said frame members remote from said hinge construction, a rod carried by one of said frame members and extending beyond said hinge construction and adjacent said other frame member, a pair of gauge stops, and a bracket carried by said other frame

member and supporting said stops one above and the other below the end of said rod.

5. In a road testing machine, the combination of two elongated longitudinally aligned frame members, a hinge construction pivotally connecting the adjacent ends of said members, a wheel rotatably mounted in said hinge construction, an additional wheel rotatably mounted on the end portion of each of said frame members remote from said hinge construction, a rod carried by one of said frame members and extending beyond said hinge construction and adjacent said other frame members, a pair of gauge stops, and a bracket carried by said other frame member and supporting said stops one above and the other below the end of said rod, said stops comprising screws adjustable in said bracket towards and from said rod permitting desired amounts of movement of said rod end.

6. In a road testing machine, the combination of an elongated frame having a hinge dividing the frame into two connected parts foldable adjacent each other when the machine is not in use, wheels carried by and supporting the frame at its end portions and at an intermediate point when in its open position, and devices having relative movement and carried respectively by the two parts of the frame and indicating changes in the elevation of one of said wheels relatively to the others of said wheels.

7. In a road testing machine, the combination of an elongated frame having a hinge dividing the frame into two connected parts foldable adjacent each other when the machine is not in use, wheels carried by and supporting the frame at its end portions and at an intermediate point when in its open position, and devices having relative movement and carried respectively by the two parts of the frame and indicating changes in the elevation of one of said wheels relatively to the others of said wheels, said devices comprising a member extending from one of said parts beyond said hinge and adjacent the other of said parts, and a gauging device carried by said other part adjacent said member.

8. In a road testing machine, the combination of an elongated frame having a hinge dividing the frame into two connected parts foldable adjacent each other when the machine is not in use, wheels carried by and supporting the frame at its end portions and at an intermediate point when in its open position, and devices having relative movement and carried respectively by the two parts of the frame and indicating changes in the elevation of one of said wheels relatively to the others of said wheels, said parts and devices being so proportioned that the relative movement of said devices in any case is substantially equal to the change in eleva-

tion of one of said wheels relatively to the others thereof.

9. In a road testing machine, the combination of an elongated frame having a hinge dividing the frame into two connected parts foldable adjacent each other when the machine is not in use, wheels carried by and supporting the frame at its end portions and at an intermediate point when in its open position, and devices having relative movement and carried respectively by the two parts of the frame and indicating changes in the elevation of one of said wheels relatively to the others of said wheels, said devices comprising a member extending from one of said parts beyond said hinge and adjacent the other of said parts, and a gauging device carried by said other part adjacent said member, said parts and devices being so proportioned that the relative movement of said devices in any case is substantially equal to the change in elevation of one of said wheels relatively to the others thereof.

10. In a road testing machine, the combination of an elongated frame having a hinge dividing the frame into two connected parts foldable adjacent each other when the machine is not in use, wheels carried by and supporting the frame at its end portions and at an intermediate point when in its open position, a guideway carried by one of said frame parts and directed towards the other of said frame parts, a rod movable in said guideway to extend beyond said hinge and adjacent the other of said frame parts, and gauging devices carried by said other frame part for indicating relative movement between said rod and said gauging devices, said rod being at least as short as the frame part supporting it and contained within the length of said supporting frame part when the frame parts are in folded condition.

11. In a road testing machine, the combination of an elongated frame having a hinge dividing the frame into two connected parts foldable adjacent each other when the machine is not in use, wheels carried by and supporting the frame at its end portions and at an intermediate point when in its open position, a guideway carried by one of said frame parts and directed towards the other of said frame parts, a rod movable in said guideway to extend beyond said hinge and adjacent the other of said frame parts, and gauging devices carried by said other frame part for indicating relative movement between said rod and said gauging devices, said rod being at least as short as the frame part supporting it and contained within the length of said supporting frame part when the frame parts are in folded condition, said gauging devices comprising a bracket carried by said other frame part, and screws carried by said bracket above and below said rod respectively

and movable towards and away from said rod as desired.

12. In a road testing machine, the combination of an elongated frame having a hinge dividing the frame into two connected parts foldable adjacent each other when the machine is not in use, wheels carried by and supporting the frame at three points when in its open position, and devices having relative movement and carried respectively by the two parts of the frame and indicating changes in the elevation of one of said wheels relatively to the others of said wheels, one of said wheels having its axis coincident with said hinge axis, and the others of said wheels being equidistant from said hinge axis.

In witness whereof, I hereunto subscribe my name this 13th day of December, A. D. 1928.

GEORGE N. LAMB.
